DESIGN FOR A STERILIZER FOR BOTTLES OR THE LIKE

Charles A. Pipenhagen, Chicago, Ill.

Application June 6, 1936, Serial No. 63,074

Term of patent 14 years

To all whom it may concern:

Be it known that I, Charles A. Pipenhagen, a citizen of the United States, residing at Chicago, in the county of Cook and State of Illinois, have invented a new, original, and ornamental Design for a Sterilizer for Bottles or the Like, of which the following is a specification, reference being had to the accompanying drawing, forming part thereof.

Fig. 1 is a top plan view of a sterilizer, for bottles or the like, embodying my new design; and

Figs. 2 and 3 are both side elevational views thereof.

I claim:

The ornamental design for a sterilizer for bottles or the like as shown.

CHARLES A. PIPENHAGEN.
